UNITED STATES PATENT OFFICE.

HOWARD D. GIRVAN, OF BEAVER FALLS, PENNSYLVANIA.

INTERNAL-COMBUSTION ENGINE.

1,266,676.

Specification of Letters Patent. Patented May 21, 1918.

Application filed June 5, 1917. Serial No. 172,399.

To all whom it may concern:

Be it known that I, HOWARD D. GIRVAN, a citizen of the United States, and a resident of Beaver Falls, in the county of Beaver and State of Pennsylvania, have invented new and useful Improvements in Internal-Combustion Engines, of which the following is a specification.

My invention is an improvement in internal combustion engines, and has for its object to provide an engine of the character specified provided with valve mechanism having the simplicity of the puppet valve with the efficiency of the sleeve valve, and wherein the valve cannot get out of time, is not affected by carbon and needs no grinding.

In the drawings:

Figure 1 is a vertical section through the improved engine;

Fig. 2 is a perspective view of the valve and sleeve separated;

Fig. 3 is a similar view of the valve and sleeve assembled;

Fig. 4 is a section on the line 4-4 of Fig. 3.

In the present embodiment of the invention, the engine has the usual cylinder 1 in which is mounted the piston 2, the piston being connected to the crank shaft 3 by means of the rod 4, and the cylinder has the usual spark plug 5.

A valve chamber 6 of cylindrical form is arranged adjacent to the cylinder and integral therewith in the present instance, and the cylinder and the chamber are connected to the crank casing 7. This chamber has a port 8 opening into the cylinder, and a port 9 which may be connected with the carburetor, and these ports 8 and 9 are in alignment diametrically of the chamber. Within the valve chamber is arranged a sleeve or cylindrical casing 10, and this sleeve has oppositely arranged ports 11 which register with the ports 8 and 9. The valve 12 which is a cylindrical casing is arranged within the sleeve, and the said valve has one end closed, as indicated at

13, and to this end is connected the stem 14 of the valve. The stem passes through the closed lower end of the valve 10, and is provided with a head 15 in the crank case, which is engaged by a cam 16 on a cam shaft 17 driven from the crank shaft in any suitable manner. The valve has oppositely arranged ports 18 adapted to register with the ports 11 of the sleeve 10 and with the ports 8 and 9 of the valve casing, and heads 19 are arranged transversely of the casing at the ports, to constrain the mixture to pass directly to the cylinder.

A coil spring encircles the stem 14 between the closed lower end of the sleeve and a stop 20 on the rod or stem, and it will be evident that when the valve is moved into open position by the cam it will be returned by the spring. It will be obvious that the valve might be operated by a connecting rod, and the improved valve cannot get out of time and is not affected by carbon. For this reason it needs no grinding.

I claim:

In an internal combustion engine, a cylinder having a valve chamber adjacent thereto and provided with diametrically opposite ports communicating with the cylinder and with a source of fuel supply, a fixed sleeve in the chamber and having ports registering with the ports of the chamber, a valve of cylindrical form mounted to reciprocate within the sleeve and having a transverse port for placing the ports of the sleeve in communication with each other, the inner ends of the valve and the sleeve being closed, and the valve having a stem extending through the closed end of the sleeve, said valve being adapted to be moved in one direction by a cam, and a spring arranged between the stem and the closed end of the sleeve for moving the valve in the opposite direction.

HOWARD D. GIRVAN.
